[57] **CLAIM**

The ornamental design for a programmable multimeter
housing, as shown and described.

DESCRIPTION

FIG. 1 is a perspective view from above and one side of
a programmable multimeter housing showing my new
design;

FIG. 2 is a top plan view thereof on an enlarged scale;
FIG. 3 is a bottom plan view thereof on an enlarged
scale;

FIG. 4 is a front elevational view thereof on an enlarged
scale;

FIG. 5 is a rear elevational view thereof on an enlarged
scale;

FIG. 6 is a side elevational view thereof on an enlarged
scale, the opposite side being a mirror image.

Fig. 1.

Fig. 2.

Fig. 3.

Fig. 4.
